INVENTOR

William H. Rodden,

By Jas. S. Brown, his Attorney.

UNITED STATES PATENT OFFICE.

WILLIAM H. RODDEN, OF TORONTO, ONTARIO, CANADA.

STILE FOR WIRE FENCES.

SPECIFICATION forming part of Letters Patent No. 286,226, dated October 9, 1883.

Application filed November 21, 1882. (No model.)

To all whom it may concern:

Be it known that I, WILLIAM H. RODDEN, of Toronto, in the county of York and Province of Ontario, Canada, have invented an Improved 5 Stile for Wire Fences; and I do hereby declare that the following is a full and exact description of the invention, reference being had to the accompanying drawings, making part of this specification—

10 Figure 1 being a side view of a portion of a wire fence constructed with my improvements; Fig. 2, a cross-section thereof in a plane indicated by the line $x\ x$, Fig. 1; Fig. 3, a cross-section in a plane indicated by the line $y\ y$, Fig. 1; Fig. 4, a partial side view, showing an 15 addition to the construction shown in the other figures.

Like letters designate corresponding parts in all the figures.

20 My improvements are adapted especially to wire and barbed-wire fences.

My improved stile for crossing over wire fences is constructed as follows: At any place or interval where it is desired to have a stile 25 two posts are placed at a short distance apart, say three feet. Then, at proper heights, step-cleats or strips E E are attached to the adjacent posts on both sides, as shown in Figs. 1 and 3, when the wires extend across these stile-30 posts. These cleats or strips are to be so located as to be in front of and shield the wires from the feet of the persons crossing over, and

in the case of a barbed-wire fence to shield the persons against injury by the wire barbs. Preferably, and as shown by dotted lines in the 35 drawings, the rail or joint cap is here made to extend so as to overlap on the regular cap-rail at each end, where it is secured thereto. It is also secured to the stile-posts through the regular cap-rail. This gives double strength 40 and firmness to the fence where the stile is located, and where additional strength is required. This construction of stile is not only simple and cheap, but enables persons—females as well as males—to cross over conveniently 45 and safely; or my stile for crossing wire fences may be constructed on single posts by attaching the cleats or steps thereto; but this will will not be as useful, safe, convenient, or durable a method as the one first described. 50

What I claim as new, and desire to secure by Letters Patent, is—

In combination with a wire fence, a stile composed of steps E E, attached to the sides of adjacent posts and shielding the fence-wires, substantially as and for the purpose herein specified. 55

Done at Toronto, Canada, this 4th November, 1882.

W. H. RODDEN.
